US00D595291S

(12) **United States Design Patent**
Takemasa

(10) **Patent No.:** US D595,291 S
(45) **Date of Patent:** ** Jun. 30, 2009

(54) **PORTABLE COMPUTER**

(75) Inventor: **Hirofumi Takemasa**, Kadoma (JP)
(73) Assignee: **Panasonic Corporation**, Kadoma-shi (JP)
(**) Term: **14 Years**
(21) Appl. No.: **29/306,545**
(22) Filed: **Apr. 10, 2008**
(30) **Foreign Application Priority Data**
Feb. 1, 2008 (JP) 2008-002227

(51) **LOC (9) Cl.** 14-02
(52) **U.S. Cl.** D14/346

(58) **Field of Classification Search** ..... D14/341, D14/342, 343, 344, 345, 346, 347, 138 R, D14/138 AA, 138 AB, 138 AC, 138 AD, D14/138 C, 138 G, 315, 316, 320, 331, 333, D14/334, 335, 338, 339, 340, 387, 390, 391, D14/392, 393, 394, 395, 396, 397, 398, 399, D14/400, 401, 406, 420, 426, 427, 428, 429, D14/432, 439, 440, 441, 453, 454, 455, 456, D14/457, 496, 130, 137, 142, 150, 151, 203.1; D14/203.3, 203.4, 203.5, 203.6, 203.7, 238.1, D14/247, 248, 250, 902, 218, 125, 126; D13/168, D13/171; D18/7; D21/324, 329, 330, 331, D21/333; D10/65; 455/556.1, 556.2, 566, 455/575.1, 575.3, 575.4, 90.3; 341/22; 379/433.04, 379/433.06, 433.07, 433.11, 433.12, 433.13, 379/910, 915, 916; 348/14.02, 207.1, 552; 345/169, 168, 901

See application file for complete search history.

(57) **CLAIM**

The ornamental design for a portable computer, as shown and described.

DESCRIPTION

FIG. 1 is a front perspective view of the front, right side and top plan view of a portable computer showing my new design;

FIG. 2 is a rear perspective view thereof;

FIG. 3 is a front view thereof;

FIG. 4 is a top plan view thereof;

FIG. 5 is a left side view thereof;

FIG. 6 is a right side view thereof;

FIG. 7 is a bottom view thereof; and,

FIG. 8 is a rear view thereof.
